THERMO-ELECTRIC HEATING AND COOLING BODY.

1,120,781.

Specification of Letters Patent. Patented Dec. 15, 1914.

Application filed April 3, 1912. Serial No. 688,298.

To all whom it may concern:

Be it known that we, WALDEMAR WILLY EDMUND ALTENKIRCH and GEORG RICHARD GEHLHOFF, both subjects of the German Emperor, and residents of Fredersdorf, near Berlin, and Danzig-Langfuhr, respectively, Germany, have invented certain new and useful Improvements in Thermo-Electric Heating and Cooling Bodies, of which the following is a specification.

When an electric current is sent through a thermoelectric couple, as is well known, the one junction is heated and the other cooled. It has heretofore been proposed to employ this effect, named after its discoverer, Peltier, for cooling railway cars for example. Such attempts must, however, necessarily fail, particularly in the case of a low thermoelectric power of the substances employed, and owing to the great thermic conductivity of the thermoelectrically operative substances in the arrangement of thermoelectric couples known heretofore which admit of only small reductions of temperature being obtained, in the case of copper and iron, for example, not even 2° centigrade. Even though a thermoelectric cooling apparatus cannot have the efficiency of modern mechanical refrigerating plants, such a thermoelectric cooling apparatus would, however, be very suitable for household requirements and the like in consequence of its hygienic advantages, its absence of noise and smell, its simple manipulation and constant readiness for operation. An arrangement is therefore described herein-after which admits of producing any desired reduction of temperature starting from a given temperature of the cooling medium.

The idea on which the subject matter of the invention is based is the consideration that the heating effect of a thermoelectric couple through which an electric current is sent is always greater than the cooling effect. Therefore, in order to obtain a favorable utilization of the heating and cooling effects while simultaneously using as little material as possible, not only must the hot junction be made larger than the cold, preferably in such a ratio that the superficial areas of the surfaces are approximately proportional to the ratio of the heating and cooling action, but the section from the hot

to the cold junction must taper down correspondingly.

If the sections of the individual couples were made equal throughout and the superficial area at the hot junction were made as great as the heating effect demands, the amount of material required to constitute a couple would increase in the ratio of the square of the superficial area of the elements. Such a couple would be very inefficient. In addition, those substances of high thermoelectric power which are specially valuable for the present invention are more or less expensive. Therefore, a form of the couple which tapers down toward the cold junction will preferably be selected, for instance, a cone or wedge-shape, in order to keep the amount of material as low as possible. The junction may, in order to improve the dissipation of the heat toward the outside, be cut open in known manner and connected with good conductors of heat, e. g., copper strips. Any desired number of such wedge-shaped couples may be arranged beside or behind one another for increasing the working voltage, thus obtaining the form of a hollow cylinder, for example, the hot junctions of which are located outside and the cold junctions of which are located inside. Moreover, if the operative substances are arranged alternately between metal rings or tubes of any desired section (annular, polygonal, corrugated or elliptical and so on) so that the couples attain the form of closed hollow rings, any desired ratio between the hot and cold surfaces can be readily obtained. Furthermore, such a body can be easily manufactured even in case it is made of brittle and fragile material and it is very durable. Now since the conductivity of heat of the various substances varies, the substances must be given different sections to enable a good cooling effect to be obtained.

In the case of cylindrical bodies the section can be changed by changing the thickness of wall of the operative substances. For a couple of bismuth and antimony the most favorable conditions are reached when the ratio of the section of bismuth to the antimony is 2.46 to 1.

In the accompanying drawing which illustrates the invention, similar letters refer to similar parts throughout the several views.

Figure 1 is a longitudinal section of a heating and cooling body of cylindrical shape. Fig. 2 is a diagrammatic view of an apparatus embodying the invention, and Fig. 3 is a longitudinal section of a modification of the form shown in Fig. 1.

The annular, positive, operative bodies (such as antimony) are designated *a*, and the negative (say bismuth) *b*, *c*, designates metal 10 rings (copper) and *d* insulating disks (paper, mica and the like). The poles or leads for the current are arranged at +*e* and -*e*. Such a tube can be very easily manufactured, for example, the substances can be 15 cast between the staggered metal rings or even be pressed in them when in a powdered condition. If desired, the outer copper rings may be heated and pushed over the previously prepared members, so that they 20 firmly encircle the latter when cooling down, or the usual soldering method, galvanization, or amalgamating may be employed, and so on. The inner copper rings may be inserted in similar manner after being 25 cooled. By means of these couples of cylindrical, polygonal, elliptical and similar shapes all losses with the exception of the unavoidable losses due to the inner conduction of heat are almost completely avoided. 30 It is very important that the absorption of the heat should take place exclusively at the coldest part of the couple and the delivery of heat at the warmest part, and that no exchange of heat should take place between 35 them, the space between the members being completely filled with insulating material. Besides there is the additional advantage of the hot outer and cold inner junctions being completely separated, so that these may be 40 at different pressures or be washed by various liquids.

If a cold liquid, *e. g.*, salt water, be passed through the interior of the body, it is cooled on its way and can be led to a 45 place at which it can absorb heat and thus exert a cooling effect. Such an arrangement is diagrammatically represented in Fig. 2. This arrangement would be sufficient, for example, if merely small quantities of ice are intended to be produced at 50 considerably long intervals of time. The great heat absorbing power of the outer parts of the body suffices, in this event, for absorbing the heat produced for some time. 55 Preferably, the inner junctions should be located as near as possible to the axis of the cylinder in order to reduce the heat absorbing power of the inner parts of the body as much as possible. The cooling then takes 60 place very quickly. During the intervals or pauses in working, the body may give off the heat absorbed to the air to a sufficient extent. For increasing the conductivity of 65 heat at the hot junctions, it is however, of advantage to cool the hot junction, for ex-

ample by circulating liquids. If 75% Sb (antimony) + 25% Cd (cadmium) be employed as the positive alloy and 90% Bi (bismuth) + 10% Sb (antimony) as the negative alloy, and if the inner radius be 0, 5 70 cms. and the outer 3 cms. and the amount of the positive alloy be 3.4 of that of the negative, it would be necessary for keeping a cupboard cool that the cooling body be about 30 cms. high and that a current of 56 75 watts be consumed.

With a cooling body such as described only minor differences in temperature can be produced particularly when the thermoelectric power of the substances employed is small and the consumption of current near the critical temperature difference is rather considerable. By the aid of the following arrangement, however, any desired reduction in temperature can be obtained, starting 80 from a given temperature of the cooling agent, or the expenditure of electrical energy for a cooling effect at the same difference in temperature can be considerably reduced. For example, if the cylinder represented in Fig. 1 is surrounded by a second similar cylinder, the cold junctions of the second cylinder will be located directly next to the hot junctions of the first cylinder. 85

If the two cylinders are connected in parallel so that they must have the same voltage and number of couples, each individual junction or seam will, when the outer column is shifted for one member and the current changed correspondingly, have exactly 90 the same potential and the same height as the corresponding next junction. It is consequently unnecessary to provide for insulation. Rather the same copper ring *c* may simultaneously constitute both the outer 100 boundary for one couple of the inner cylinder and the inner boundary for the corresponding couple of the adjacent outer cylinder. The losses are thereby exceedingly 105 small and at the same time any defects and 110 inequalities in the material are automatically equalized by the inner distribution of current. Such a thermic cascade connection in the case of electric parallel connection is practicable not only in cylindrical couples. 115 Though the form of the closed cylinder is very advantageous as regards durability, choice of material and avoidance of losses, it is nevertheless not essential for the effect 120 of this cascade connection, whether the rings are closed or whether they are subdivided for increasing the number of the couples and the working voltage, so that the body consists perhaps of sectors of a cylinder. 125

Fig. 3 shows a longitudinal section of a 130 body of this description which may be cylindrical by way of example. The annular, positive operative bodies are designated *a* and the negative *b*, *c* are metal rings (copper), which serve for electrically connecting 130

the couples, and d are neutral disks serving for insulation. In this manner any desired number of such columns can be arranged one within the other.

- 5 The operation of this body is as follows: When a current is sent at $+e$ into this double row of couples connected in series parallel, a distributing of the current occurs. The strongest current passes through the outermost row of the thermoelectric couples because here it meets with the largest cross section, and the weakest passes through the innermost row. Thus, a strong current flows through each ring c inside this body from 10 b to a of the outer column, and a weaker from a to b of the inner column. The stationary condition, which is created in this body, is such that on each double junction owing to the "Peltier-effect" of that element or couple traversed by the stronger current is produced such as excess of cold, as is necessary for neutralizing the heat given on the next following junction.

15 The total difference of temperature produced is, however, for 3 couples for example 25 3 times as great and at n couples n times as great as that produced in each individual couple, because in consequence of the exceedingly great transmission of heat obtained by the arrangement described between the junction of contiguous couples the 30 temperatures of these junctions cannot be materially different one from another. If for certain substances there is a temperature difference of 4° centigrade between the hot 35 and cold junction and if the temperature of the outer hot junction is maintained constant at 6° C. by cold water, the cold junction of the outer body will have a temperature of 2° C. The hot junction of the second body contacting with it, the cold junction of which then is at -2° C. has the same temperature etc. Theoretically, there is absolutely no limitation to this process, so that by increasing the number of columns even for small 40 thermoelectric powers, though in this case with very great consumption of energy and cooling water, it is possible to obtain any desired diminution of temperature from a given temperature of the cooling medium. The larger the number of such columns that are connected one with another, the less the consumption of energy, in the case of the higher attainable thermoelectric powers for 45 not very great temperature differences the best results are approximately obtained with quite a small number, say two or three columns, connected one within the other.

50 Particularly for small thermoelectric powers it is most advantageous when the differences in temperature of one column is approximately equal to that of the column connected therewith in parallel. For this purpose the resistance of each outer column 55 is made smaller than that of the preceding

approximately in the ratio of the heating effect to the cooling effect of the inner column. For instance when the total cross section of the couples is constant the length of each couple must be smaller in the said ratio. The couples having the lowest temperature are the longest.

55 With the same material as mentioned in the above specified example, the internal radius of a double body is 1.1 cm. the intermediate radius 3 cms. and the other 5 cms. Accordingly, for keeping one cupboard cool a total height of about 15 cms. is required and an efficiency of current of 38 watts.

The body requires strong currents but 80 very low voltages. It therefore can be operated by a branch of any main conductor, whereby the economy of operation is increased still further.

85 Now since the production of heat at the outer hot junction is always larger than the expenditure of energy by the amount of the cooling effect of the inner cold junction, this thermoelectric body is well adapted for heating, preparing hot water, etc., where- 90 by a saving of electric energy is obtained in comparison with heating by Joule's system. It is greater the less the difference in temperature, and amounts for example, in the case of a thermoelectric power of 150-160 95 effective microvolts and 10° C. temperature difference to about 50%. In the case of this reversible electric heating, it is ob- 100 viously necessary to lead away the quantity of calories saved to the outer heat or to the cooling water, that is to say, to heat the 105 cold junctions directly or indirectly by means of these natural sources of heat, if it is not possible to make simultaneous use of the cooling effect.

105

We claim:

1. A thermo-electric couple comprising annular elements forming the couples in combination with metal rings electrically connecting and covering the peripheries of 110 the couples.

2. A thermo-electric couple comprising substantially annular elements forming the couples, in combination with metal rings shrunk onto the peripheral inner and outer 115 surfaces of each pair of elements, forming both an electrical and a rigid mechanical connection for the elements.

3. In combination, a plurality of concentric thermo-electric couples, the hot joint of 120 one couple being adjacent the cold joint of another couple.

4. In combination, a plurality of concentric, adjacent thermo-electric couples whose hot joints are of greater area than their cold 125 joints and the hot joint of one couple is adjacent the cold joint of the adjacent couple.

5. In combination, a plurality of concentric, adjacent thermo-electric couples whose hot joints are of greater area than the cold 130

joints, the larger hot joints of one couple being in conductive relation to the smaller cold joint of the adjacent couple.

6. A thermo-electric couple for cooling, comprising the two elements of the couple, having a cold junction of less area than the hot junction and means for passing a current of electricity through the couple.

7. A thermo-electric heating and cooling body, comprising thermo-electric couples, junctions for the couples, the surface of the heat yielding junctions being larger than the junctions absorbing heat at the ratio of the production of heat to the cooling effect.

8. A thermo-electric heating and cooling pile, composed of a plurality of heating and cooling couples connected in parallel to a source of electricity and disposed to contact with one another and to form outer and inner columns, the hot junction of the inner couple arranged adjacent the cold junction of an outer couple, the resistance of each outer column being less than that of the preceding approximately in the ratio of the

heating effect to the cooling effect of the inner column.

9. A thermo-electric heating and cooling pile comprising adjacent series of couples arranged in juxtaposition, with the hot junctions of the couples of one series adjacent the cold junctions of the juxtaposed series.

In testimony that I claim the foregoing partly as my invention, I have signed my name in the presence of two subscribing witnesses.
